UNITED STATES PATENT OFFICE

JOSEPH BERGER, OF UTICA, NEW YORK, ASSIGNOR TO UNION SPECIAL MACHINE COMPANY, OF CHICAGO, ILLINOIS, A CORPORATION OF ILLINOIS

LOOPER MECHANISM FOR SEWING MACHINES

Application filed October 16, 1926. Serial No. 142,051.

The invention relates to new and useful improvements in a looper mechanism for sewing machines, and more particularly a looper mechanism wherein a threaded looper cooperates with a plurality of needles.

An object of the invention is to provide a looper operating mechanism wherein the looper is moved at a relatively high speed and at substantially a uniform high speed while the point thereof is entering each one of the needle thread loops.

A further object of the invention is to provide a looper operating mechanism of the above type wherein the looper is oscillated by an eccentric member on a rotating shaft.

A still further object of the invention is to provide a looper operating mechanism of the above type wherein the variable movement imparted to the looper is accomplished by means of an oscillating arm moving about a center eccentric to the center of the oscillating shaft carrying the looper, and wherein said arm has a sliding connection with the looper shaft for oscillating the same, which sliding connection moves toward and from the center of the looper shaft for increasing the speed of the looper at a predetermined time.

These and other objects will in part be obvious and will in part be hereinafter more fully disclosed.

In the drawings which show by way of illustration one embodiment of the invention—

Figure 1 is a side view of a machine embodying my improved looper operating mechanism;

Fig. 2 is a sectional view on the line 2—2 of Fig. 1;

Fig. 3 is a view, in part similar to that shown in Fig. 2, but showing the looper operating eccentric at a different position in its rotation;

Fig. 4 is a sectional view on the line 4—4 of Fig. 1;

Fig. 5 is a sectional view on the line 5—5 of Fig. 3;

Fig. 6 is a diagrammatic view showing the operating devices for the looper with the looper shown at the forward end of its stroke

in full lines, and at the rear end of its stroke in dotted lines;

Fig. 7 is a similar view, but showing the position of the parts when the looper point is about to enter the needle thread loop of the first needle, and

Fig. 8 is a diagrammatic view showing three needles, and the looper, and indicating in broken lines the path of movement of the point of the looper.

The invention is directed to a looper operating mechanism for a multiple needle sewing machine, wherein a thread carrying looper cooperates with all of the needles, entering first one needle thread loop and then another, and so on, with the other needles, if more than two needles are used. It is preferably applied to a three-needle machine for making a covering stitch used for seaming knit wear. It is desirable to operate the looper by an eccentric member on the main shaft, and when the eccentric member alone is used for operating the looper, the looper will increase in its speed from its retracted position to a point midway of its stroke. In the present invention, I have provided devices between the eccentric and the looper which cause the looper to be speeded up just before the point enters the first needle thread loop to substantially its maximum speed, and the looper is maintained substantially at this speed until it is well into the last needle thread loop, after which it comes to the end of its stroke with a decreasing speed. I accomplish this variable speed in the looper by means of a swinging arm which is oscillated by the eccentric member. This arm is pivoted at a point eccentric to the axis of the looper shaft. On the looper shaft are guides in which a bar can slide radially of the looper shaft, and the end of this bar is connected to the end of the arm, so that as the arm oscillates, it will oscillate the looper shaft. Inasmuch as the bar slides radially in its connection to the looper shaft, it will be apparent that the point at which power is applied to the looper shaft for oscillating the same moves in and out toward the center of the shaft. By properly positioning the arm relative to the axis of the looper supporting

shaft, I am able to increase the speed of the looper through the moving of the point of connection to the looper shaft toward the center thereof, just before the point of the looper enters the first needle loop, and to maintain this increased speed until the point of the looper is well into the last needle thread loop.

Referring more in detail to the drawings, 10 I have shown the invention as applied to a sewing machine which consists of a supporting standard 1 carrying a housing 2 at its upper outer end, and this housing is provided with a main operating shaft 3 which is rotated by a belt wheel 4. Carried by the housing 2 is a depending member 5, and this depending member 5 carries a work supporting arm 6. A looper operating shaft 7 is journaled in this work supporting arm, and on 20 the end thereof is a thread carrying looper 8.

The machine is provided with a needle bar 9 which is preferably reciprocated by a lever connected to a crank on the main shaft 3, and said lever is so disposed relative to this 25 shaft which actuates the same, that the needle is given a more rapid upward movement than its downward movement. This greatly aids in the freeing of the needles from the material quickly to permit the feed of the 30 material. This quick movement of the needle bar, however, is not essential to the present invention, but when such a structure is used for reciprocating the needle, it is quite essential that the looper shall be speeded up so 35 as to get into the three needle loops, if three needles are used, very quickly.

On the main shaft is an eccentric member 10 which as illustrated is in the form of a crank, although some other type of eccentric 40 member might be used. Connected to this crank is a link 11, and the link 11 is in turn connected to a ball stud 12 on the outer end of an arm 13. The arm 13 is formed as a 45 part of a yoke 14. The yoke 14 has two sleeves 15 and 16 which are in alinement, and a short stub shaft 17 is secured to the sleeve 16 by a screw 18, while a short stub shaft 19 is secured to the sleeve 15 by a screw 20. These shafts 17 and 19 are mounted in suitable 50 bushings carried by the frame of the machine. This forms a support which permits the arm 13 to oscillate about the center of the shafts 17 and 19 as an axis. As the crank rotates, the arm 13 will be oscillated.

The looper shaft 17 is provided with a head 21 which is formed with a radial channel 22. A bar 23 is located in this channel, and the outer end of the bar 23 is connected to the outer end of the arm 13 at 24. The 60 shank of the ball stud 12 may extend through the arm 13 and serve as a connection for this bar 23. When the arm 13 is oscillated, the ball stud 12 will, of course, move in the 65 arc of a circle about the center of the shaft 17 as an axis. Inasmuch as this axis is eccen-

tric to the center of oscillation of the looper shaft, the ball stud 12 will move toward the axis of the looper shaft on the first part of its downward movement, and this will cause the bar 23 to slide in the channel head, 70 and the point of connection to the looper shaft for oscillating the same moves toward the axis of the looper shaft. It will be apparent that if the ball stud had a uniform speed of travel, this inward movement of the ball stud toward the axis of the looper shaft would increase the speed of the looper as 75 the arm 13 oscillates. As soon as the ball stud 12 passes a line passing through the axis of the looper shaft, and the axis on which the arm 13 oscillates, then the ball stud will move out away from the axis of the looper, and the bar 23 will slide outward to permit this movement. The diagrammatic views in Figures 6 to 8 will possibly 80 make the invention more clear. In Fig. 8, three needles n , n' and n'' are shown, and cooperating with these three needles is the thread carrying looper 8. This thread carrying looper is of the usual type and is moved into the needle thread loops, then laterally to avoid the needle, and is then retracted out of the needle thread loops in the usual manner, so far as concatenation of the looper and 85 needle threads is concerned.

It will be apparent from Fig. 8, that the looper point enters first the loop of thread of the needle n , then the loop of thread of the needle n' , and then the loop of thread of the needle n'' . The needles are set at different heights, as is customary in this type of machine, to aid in the looper engaging all three loops, one after the other. This, however, is not quite sufficient in a high speed machine, and the present invention is directed to means for speeding up the looper when the point thereof reaches the position indicated at b in Fig. 8. The looper point when completely retracted is at the point a , and when at the end of its forward reciprocation, it is at the point d . The present mechanism increases the speed of the looper, beginning substantially at the point b in its path of travel, and the speed is maintained at a substantially uniform high speed, 100 until the point c is reached, where the looper is well into the needle thread loops. When the looper point is at the point a in its path of travel, that is, completely retracted, the crank 10 is at the broken line position in Fig. 6, and when the looper is at the forward end of its stroke, then the crank is at the full line position shown in this figure. Starting with the crank in the broken line position 105 in this figure, it will be noted that as the crank rotates, the arm 13 approaches the line x , x , where the ball stud is in alinement with the axis of the looper shaft and the shaft 17 which supports the arm 13. During 110 this time, the ball stud is moving closer to 115 the center of oscillation of the looper shaft, and this will increase the speed of the looper. When the ball stud reaches the line x , x , the arm 13 is at the full line position, and the ball stud is moving away from the center of oscillation of the looper shaft, and this will decrease the speed of the looper. 120 During this time, the ball stud is moving closer to the center of oscillation of the looper shaft, and this will increase the speed of the looper. When the ball stud reaches the line x , x , the arm 13 is at the broken line position, and the ball stud is moving away from the center of oscillation of the looper shaft, and this will decrease the speed of the looper. 125 During this time, the ball stud is moving closer to the center of oscillation of the looper shaft, and this will increase the speed of the looper. When the ball stud reaches the line x , x , the arm 13 is at the full line position, and the ball stud is moving away from the center of oscillation of the looper shaft, and this will decrease the speed of the looper. 130

the center of the looper shaft, and the bar 23 is sliding radially to permit this movement. Therefore, the speed of the looper point is increasing by reason of the inward movement of the ball stud toward the axis of the looper shaft. The speed of travel of the link 11 is also increasing as the crank 10 increases in its speed of movement in a direction lengthwise of the link 11 until it has 5 passed through an arc of substantially ninety degrees, or has reached the point indicated at e in Fig. 6 of the drawings. The increased speed due to the inward movement of the ball stud toward the center of the looper shaft, is therefore, added to the increase of speed of the link 11 imparted thereto by the crank 10. When the point of the looper, therefore, is about to enter the first needle thread loop, the speed of the looper point is 10 increased well up to its maximum. The crank 10 is substantially at the position f indicated in Fig. 6 when the ball stud is at the line x, x . After the ball stud passes the line x, x , then said ball stud will move away 15 from the center of the looper shaft, and would tend to decrease the speed of the shaft, but the crank 10 is moving from the point f on toward the point e in its circular travel and approaching the point of highest speed 20 which it imparts to the link 11. Therefore, the speed of the point of the looper will be maintained substantially uniform at this high speed at which it entered the first needle thread loop until after the looper point has 25 entered the needle thread loop of the last needle and is well into the same, then the speed of the looper will decrease, owing to the fact that the crank is moving from the point e in Fig. 6 to the position indicated 30 in full lines in the drawings, and the ball stud is continuing to move away from the center of the looper shaft.

Of course, the retracted movement of the looper will also have a variable speed similar 45 to that of its forward movement. This enables the needles to move down into the triangle formed in the looper thread, after which the needle thread loops on the looper may be quickly shed from the looper. The particu- 50 lar advantage, however, of the looper operating mechanism is in the movement of the looper quickly into the needle thread loops.

From the above it will be apparent that I 55 have provided a looper operating mechanism wherein the power utilized for oscillating the looper is derived from a rotating eccentric member, and the devices intermediate this rotating eccentric member and the looper 60 are so constructed as to impart a variable movement to the looper, and give thereto a substantially uniform high speed during the entire time that the looper point is passing into the needle thread loops in succession.

65 That is, from the time it is closed to the first

needle thread loop until it has passed clear through the last needle thread loop.

From the above it will be apparent that I have provided a looper movement which is especially adapted for use in a sewing machine having a cylindrical work supporting arm of small diameter. In such a machine, the radius of the looper must be relatively short as compared with what the radius might be in larger cylinders or flat bed machines. Notwithstanding the small radius of the looper, it is necessary to maintain or increase the speed of the looper, so that the looper will properly cooperate with all three needles. This increased speed of the looper permits the points of the needles to be brought very close together.

It is obvious that minor changes in the details of construction may be made without departing from the spirit of the invention as set forth in the appended claims.

Having thus described the invention, what I claim as new and desire to secure by Letters-Patent, is—

1. The combination of a plurality of threaded needles, a thread carrying looper cooperating with said needles, means for oscillating said thread carrying looper including a rotating eccentric member, a link connected thereto, a pivoted arm attached to said link and oscillated thereby, a shaft on which said looper is mounted, said shaft being set eccentric to the pivotal point of said arm, and so that as said arm oscillates, it will move relative to and across the axis of the looper shaft, and means for connecting said arm to said looper shaft.

2. The combination of a plurality of threaded needles, a thread carrying looper cooperating with said needles, means for oscillating said thread carrying looper including a rotating eccentric member, a link connected thereto, a pivoted arm attached to said link and oscillated thereby, a shaft on which said looper is mounted, said shaft being set eccentric to the pivotal point of said arm, and so that as said arm oscillates, it will move across the axis of the looper shaft, and means for connecting said arm to said looper shaft, said last-named means including a bar pivoted to said arm and having a sliding connection with the looper supporting shaft.

3. The combination of a plurality of threaded needles, a thread carrying looper cooperating with said needles, means for oscillating said thread carrying looper including a rotating eccentric member, a link connected thereto, a pivoted arm attached to said link and oscillated thereby, a shaft on which said looper is mounted, said shaft being set eccentric to the pivotal point of said arm, and so that as said arm oscillates, it will move across the axis of the looper shaft, means for connecting said arm to said looper shaft, said last-named means including a head carried

at the end of the looper operating and having a radial channel therein, and a bar slidable in said channel and pivoted to said arm adjacent the outer end thereof.

4. The combination of a plurality of threaded needles, a thread carrying looper cooperating with said needles, a shaft on which said thread carrying looper is mounted, means for oscillating said shaft including a rotating eccentric member, a link connected thereto, a pivoted yoke having an extended arm to which the link is connected, whereby the rotations of said eccentric member oscillate said arm, the axis of said pivoted yoke being disposed on the opposite side of the axis of the shaft from the free end of the arm, and so that said arm moves across the axis of the looper shaft in its oscillations, and a bar pivotally connected to said arm adjacent the outer end thereof having a sliding radial connection with the looper shaft so that the oscillations of said arm through said bar impart oscillations to said looper shaft.

5. The combination of a plurality of threaded needles, a thread carrying looper cooperating with said needles and entering the needle thread loops in succession, a shaft on which said looper is supported, a member connected to said shaft for oscillating the same, said member being shiftable radially of the shaft during the oscillations thereof, means connected to said member for oscillating the same, and a device connected to said member for shifting the same during the oscillation of the shaft, whereby the looper is given a substantially uniform relatively high speed movement where the point is entering all of the needle thread loops.

In testimony whereof, I affix my signature.
JOSEPH BERGER.
